United States Patent Office

Des. 189,150
Patented Nov. 1, 1960

189,150

SALAD SPOON

Samuel L. Gerson, Box 1827, Wilmington, Del.

Filed Mar. 16, 1959, Ser. No. 55,016

Term of patent 7 years

(Cl. D44—29)

Fig. 1 is a front view in elevation of a salad spoon embodying my new design;

Fig. 2 is a side view in elevation thereof; and

Fig. 3 is a perspective view thereof.

I claim:

The ornamental design for a salad spoon, as shown.
